UNITED STATES PATENT OFFICE

DAVID H. BROWN, OF GRAND RAPIDS, MICHIGAN, ASSIGNOR TO CENTURY FURNITURE COMPANY, OF GRAND RAPIDS, MICHIGAN, A CORPORATION OF MICHIGAN

DESIGN FOR A DESK

Application filed October 28, 1930. Serial No. 37,417. Term of patent 7 years.

To all whom it may concern:

Be it known that I, DAVID H. BROWN, a citizen of the United States, residing at the city of Grand Rapids, in the county of Kent and State of Michigan, have invented a new original, and ornamental Design for Desk, of which the following is a specification, reference being had to the accompanying drawings, forming a part thereof.

Fig. 1 is a perspective view of a desk showing my new design.

Fig. 2 is an enlarged fragmentary plan of one corner of the desk top.

Fig. 3 is an enlarged fragmentary elevation of an upper front corner of the desk, and

Fig. 4 is an enlarged fragmentary elevation of the front center rail.

I claim:

The ornamental design for a desk, as shown.

DAVID H. BROWN.
